UNITED STATES PATENT OFFICE.

MATTHIAS REDLINGER, JR., OF FREEPORT, ILLINOIS.

DESIGN FOR A PITCH-REAMER.

SPECIFICATION forming part of Design No. 32,095, dated January 9, 1900.

Application filed December 8, 1899. Serial No. 739,719. Term of patent 14 years.

To all whom it may concern:

Be it known that I, MATTHIAS REDLINGER, Jr., a citizen of the United States of America, residing at Freeport, in the county of Stephenson and State of Illinois, have invented and produced a new and original design for pitch-reamers for reaming pitch out of the metallic bushings of the bung-holes of beer-kegs preparatory to driving bungs thereinto, of which the following is a specification, reference being had to the accompanying drawings, forming part thereof.

Figure 1 is a side view of a pitch-reamer, showing my new design. Fig. 2 is a sectional view taken on line 2 2 of Fig. 1.

As shown in the drawings, the leading or material features of my design consist of a

series of radially-projecting and gradually-tapering reaming-teeth A and interdental depressions B, disposed or arranged as shown in Fig. 2, the said teeth A and depressions B being star-shaped in cross-section. 20

Having described my invention, what I claim as new, and desire to secure by Letters Patent, is—

The design for a pitch-reamer, as herein shown and described.

In testimony whereof I have signed my name to this specification in the presence of two subscribing witnesses.

MATTHIAS REDLINGER, JR.
